COVER PANEL FOR A WATER CONDITIONER CABINET

John H. Horn, Erie, Pa., assignor to Uniflow
Manufacturing Company, Erie, Pa.

Continuation-in-part of design application Ser. No. 17,517,
June 4, 1969. This application Dec. 14, 1970, Ser.
No. 26,448

Term of patent 14 years

Int. Cl. D23—01

U.S. Cl. D23—3

FIG. 1 is a front elevation of a cover panel for a water conditioner cabinet, showing my new design; and

FIG. 2 is a cross-section taken on line 2—2 of FIG. 1.

The broken lines are shown for illustrative purposes only.

This is a continuation-in-part of design application, Ser. No. D-17,517, filed June 4, 1969 and now abandoned.

I claim:

The ornamental design for a cover panel for a water conditioner cabinet, as shown and described.
